US0D1048175S

(12) **United States Design Patent** (10) Patent No.: **US D1,048,175 S**
(45) Date of Patent: ** Oct. 22, 2024

(54) **CASE SPECIFICALLY DESIGNED FOR ITEMS**

(71) Applicant: **Huihai Zheng**, Fuzhou (CN)

(72) Inventor: **Huihai Zheng**, Fujian (CN)

(**) Term: **15 Years**

(21) Appl. No.: **35/516,923**

(22) Filed: **Mar. 22, 2023**

(80) **Hague Agreement Data**

Int. Filing Date: **Mar. 22, 2023**

Int. Reg. No.: **DM/228115**

Int. Reg. Date: **Mar. 22, 2023**

Int. Reg. Pub. Date: **Apr. 21, 2023**

(30) **Foreign Application Priority Data**

Dec. 27, 2022 (CN) 202230863424.6

(51) **LOC (14) Cl.** **19-99**

(52) **U.S. Cl.**

USPC **D19/78; D19/95**

(58) **Field of Classification Search**

USPC D19/86, 90, 91, 95, 99, 78

CPC B41J 29/15; A47F 5/112; G06F 1/1607

Primary Examiner — Garth Rademaker

Assistant Examiner — Laura H Yu

(57) **CLAIM**

The ornamental design for a case specifically designed for items as shown and described.

DESCRIPTION

- 1.1 : Perspective
- 1.2 : Perspective
- 1.3 : Perspective
- 1.4 : Front
- 1.5 : Back
- 1.6 : Left
- 1.7 : Right
- 1.8 : Top
- 1.9 : Bottom

Case specifically designed for items; it is usually used to store items; 1.1 is a perspective view of a case specifically designed for items viewed from one angle; 1.2 is a perspective view of the case specifically designed for items viewed from another angle; 1.3 is a perspective view of the case specifically designed for items where the drawer of the case is in an open configuration; 1.4 is a front view of 1.1; 1.5 is a back view thereof; 1.6 is a left view thereof; 1.7 is a right view thereof; 1.8 is a top view thereof; 1.9 is a bottom view thereof.

(Continued)

The broken lines in the drawings depict portions of the case specifically designed for items that form no part of the claimed design.

1 Claim, 9 Drawing Sheets
